UNITED STATES PATENT OFFICE

159,858

AIRPLANE

Ben Newton Powell, Alpaugh, Calif.

Application May 16, 1949, Serial No. 2,702

Term of patent 14 years

(Cl. D71—1)

To all whom it may concern:

Be it known that I, Ben Newton Powell, a citizen of the United States, residing in the city of Alpaugh, county of Tulare, and State of California, have invented a new, original, and ornamental Design for an Airplane, of which the following is a specification, reference being had to the accompanying drawing, forming part thereof.

Fig. 1 is a perspective view of an airplane, showing my new design.

Fig. 2 is a top plan view thereof.

Fig. 3 is a side elevational view thereof.

Fig. 4 is a front elevational view thereof.

Fig. 5 is a rear elevational view thereof.

I claim:

The ornamental design for an airplane, as shown.

BEN NEWTON POWELL.
